UNITED STATES PATENT OFFICE.

PETER M. PETERSON, OF NARRAGANSETT PIER, RHODE ISLAND.

BOTTLE-FASTENER.

No. 823,437.

Specification of Letters Patent.

Patented June 12, 1906.

Application filed August 8, 1905. Serial No. 273,301.

To all whom it may concern:

Be it known that I, PETER M. PETERSON, a citizen of the United States, residing at Narragansett Pier, in the county of Washington, State of Rhode Island, have invented certain new and useful Improvements in Bottle-Fasteners; and I do hereby declare the following to be a full, clear, and exact description of the invention, such as will enable others skilled in the art to which it appertains to make and use the same.

This invention relates to bottle-stoppers.

One object of the invention is to provide a bottle-stopper of the bail-fastening type embodying such characteristics that when the cap of the bottle is removed from engagement with the mouth of the latter it cannot be again placed over the mouth of the bottle.

Another object of the invention resides in the provision of an exceedingly simple, inexpensive, durable, and efficient bottle-stopper of the nature stated.

With these and other objects in view the present invention consists in the combination and arrangement of parts, as will be hereinafter more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the drawings, Figure 1 is an elevation of my invention. Fig. 2 is a vertical section of the structure with the parts in elevation.

Referring now more particularly to the accompanying drawings, it will be seen that the present invention comprises a bottle 1, having the usual neck 2, which latter in the present instance is provided with oppositely-disposed lugs 3 and 4, each of which is perforated, as designated by the reference character 5, for the slidable reception of the spring-arms 6 and 7, secured to the respective eyes 8 and 9 of the yoke 10. The lower ends of these spring-arms 6 and 7 are directed upwardly, as at 11, and then outwardly, as at 12, to form a hook for engagement in the recesses 13 of the respective lugs 3 and 4, the said recesses 13 intersecting the corresponding perforations of the said lugs intermediate the upper and lower edges of the lugs.

The reference character 15 designates a bottle-cap, secured to the upper face of

which is the bail 16, whose ends are directed inwardly, as at 17, for engagement with the upper eyes 8 and 9 of the yoke 10, the said yoke 10 being adapted to be raised and lowered with respect to the neck 2 of the bottle 60 and having connection with the ring 20, embracing the neck 2 of the bottle, whereby it may be raised and lowered in the usual manner.

A wire ring 21 embraces the neck 2 of the bottle and also the spring-arms 6 and 7 beneath the yoke 10, the said ring 21 engaging the arms 6 and 7 in such a manner as to have a tendency to compress the arms 6 and 7 toward the corresponding side of the neck 2 70 of the bottle.

In order to remove the cap 15 from over the mouth of the bottle, the yoke-frame 10 is forced upwardly, causing a lifting of the cap 15 in the usual manner and the bail 16 to 75 throw the said cap downwardly upon the side of the neck of the bottle. When the yoke 10 is lifted and the cap 15 thereof thrown to the position just stated, the spring-arms 6 and 7 are lifted through the perforations 5 of the respective lugs 3 and 4 until their hooked portions 12 reach the recesses 13 of the respective lugs 3 and 4, when the said portions 12 will spring into the said recesses and prevent further movement of the yoke 85 10 and the cap 15 and also prevent a downward movement of the yoke 10, thereby preventing a replacing of the cap 15 upon the mouth or neck of the bottle.

What is claimed is—

1. The combination with a bottle having integral oppositely-disposed lugs formed upon the neck thereof, each lug having a perforation therethrough intersected by a recess arranged at a right angle to the perforation; 95 of a cap for engagement over the mouth of the neck of the bottle, a bail connected with the cap, a yoke, spring-arms connected with the yoke and extending through the perforations of the corresponding lugs, the free ends 100 of the said arms being in hooked form for engagement with the aforesaid recesses of the respective lugs when the said yoke is lifted to disengage the cap from the neck of the bottle.

2. The combination with a bottle having oppositely-disposed lugs each provided with a perforation and a recess intersecting the perforation of each lug; of a cap for closing the bottle, a bail connected with the cap, a yoke pivotally mounted upon the bottle and 110

connected to said bail, spring-arms connected with said yoke and each slidably mounted in the perforation of the corresponding lug, the free ends of each spring-arm being provided with a hook for engagement in the aforesaid recess of the corresponding lug when the said yoke is raised; and a ring embracing the neck of the bottle and engaging

the said spring-arms to force the latter normally toward the bottle.

In testimony whereof I affix my signature in presence of two witnesses.

PETER M. PETERSON.
